UNITED STATES PATENT OFFICE

169,729

READING AND EXAMINATION LAMP

Harlan F. Borin, Chicago, Ill., assignor to American Hospital Supply Corporation, Evanston, Ill., a corporation of Illinois

Application August 12, 1952, Serial No. 20,973

Term of patent 14 years

(Cl. D48—20)

To all whom it may concern:

Be it known that I, Harlan F. Borin, a citizen of the United States, residing at Chicago, Illinois, have invented a new, original, and ornamental Design for a Reading and Examination Lamp, of which the following is a specification, reference being had to the accompanying drawing, forming a part hereof.

Fig. 1 is a side elevational view of a reading and examination lamp, showing my new design;

Fig. 2 is a front elevational view thereof;

Fig. 3 is a plan view thereof; and

Fig. 4 is a horizontal sectional view taken substantially along the line 4—4 of Fig. 1.

I claim:

The ornamental design for a reading and examination lamp, substantially as shown.

HARLAN F. BORIN.
